UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SAFETY DEVICE FOR PRESSES.

1,212,176.

Specification of Letters Patent. Patented Jan. 16, 1917.

Application filed April 25, 1913. Serial No. 763,577.

101

To all whom it may concern:

Be it known that I, REUBEN B. BENJAMIN, a citizen of the United States, residing at Chicago, in the county of Cook and State of Illinois, have invented new and useful Improvements in Safety Devices for Presses, of which the following is a full, clear, concise, and exact description, reference being had to the accompanying drawing, forming 5 a part of this specification.

10 My invention relates to improvements in safety manipulating devices for intermittently operated machinery, and particularly for intermittently operating punch presses and the like.

15 One of the objects of my invention is to provide a mechanism which will insure the operator's hands being in a place of safety when the machinery is caused to operate.

20 In my co-pending application, filed April 25, 1913, Serial No. 763,576, I have shown my invention embodied in one form, in which the various parts are operated entirely by electricity. In the present embodiment I have illustrated some of the parts as 25 being mechanically operated.

25 For the purpose of disclosing my invention, I have illustrated the same applied to a punch press in the accompanying drawings.

30 In said drawings Figure 1 is a side elevation of sufficient of a punch press to illustrate the application of my invention; and Fig. 2 is a front elevation of a portion of a 35 punch press, showing in detail a certain part of my invention as applied thereto.

35 In said drawings, the machine 1 is a punch press having the usual frame 2 and a trip mechanism by means of which the 40 clutch between the punch and source of power is thrown into driving connection. The tripping mechanism may be of any of the well known constructions, and a description of the same is therefore not required 45 here, except to state that after the clutch has been once thrown and has caused the punch to descend the clutch will automatically be disconnected. This tripping mechanism is operated by an electro-magnet 4,

50 which is connected to the movable member 3 of the tripping mechanism by a connecting rod 5. The circuit of this electro-magnet, which is included in the wires 6, 7, 8 and 9, has interposed at one point a switch 10, 55 which is adapted to be held closed by a mov-

able switch arm 11 held in its raised position by a coiled spring 12. This movable switch arm, which causes the two contacts of the switch 10 to be maintained closed, is moved downward when the electro-magnet operates to trip the clutch by a projection on the lower end of the solenoid core. The downward movement of this switch arm permits the spring arms of switch 10 to open, thereby opening the circuit of the electro-magnet 60 after it has operated to trip the press. A sliding stop 13 held in its normal or projected position by a spring 14, engages over the top of the switch arm 11 after it has been pushed down, and prevents the arm from 65 being raised until the proper mechanism is operated to move the stop 13 out of the path of the switch arm and permit the switch arm to again rise under the influence of the spring 12. This operating mechanism 70 consists of a latch 15 adapted to engage the rear end of the stop 13. This latch is provided at its rear end with a rocking arm 16 pivoted at its center to the latch and having one end thereof connected by a link 17 with a 75 rocking arm 18 loosely mounted on the shaft 26. The opposite end of the arm 18 is connected by a suitable link 19 with a 80 slidable hand band 21. This hand band is supported from the top of the frame by a suitable 85 resilient support in the form of a spring 22 connected at its upper end by bolt 23 with the top portion of the frame. The opposite end of the arm 16 is connected by a link 24 with an arm 25 mounted on the end of a 90 shaft 26 extending across the front portion of the press frame. The opposite end of 95 this shaft is provided with an arm 27, which in turn is connected by the link 28 with a 100 slidable hand connector 29 supported by a coiled spring 30 in a manner similar to the connector 21. A suitable stop 31 is arranged to prevent the arm 18 from being rocked too far rearward. In addition to the switch 10 in the circuit of the electro-magnet 4, a second switch 32 is arranged in this circuit, which switch is normally opened but the contacts of which are in a position to be closed by the forward movement of the end 105 of the latch 15. It will be noted that a lateral movement and vertical movement of these connectors is permissible in addition to their forward movement, which forward and rearward movement carries with it the 110 operating arms 25 and 18. By this arrange-

ment the connectors, which are adapted to be fastened to the hands of the operator, permit a free movement of the hands of the operator and at the same time provide a means for causing the tripping of the press under certain predetermined conditions.

In operation, we will assume that the parts are in the position illustrated in the drawings, and that the operator has placed a suitable piece of material in the press to be operated upon. The operator then draws both hands backward out of the danger zone of the press. When the operator draws both hands back, the left hand will cause the shaft 26 to rotate, throwing forward the arm 25 and therefore giving a forward tendency to the upper-end of the rocker arm 16. At the same time, the moving back of the right hand will throw rearward the upper end of the arm 18, which will cause the lower end of the arm 16 to move forward. This will move the latch 15 forward, thereby causing the spring contacts of the switch 32 to close, and thereby closing the circuit through the electro-magnet 4, causing it to pull down on the movable member 3 and trip the press. As soon as the electro-magnet trips the press the extension on the lower end of its core will move the switch arm 11 downwardly, thereby permitting the spring arms of the switch 10 to open. The front end of this switch arm 11 will be caught beneath the end of the stop 13 and the arm will be prevented from again returning to close the switch under the influence of the spring 12. The operator now takes up one of the pieces of material, his hand being in a natural position for doing this, and holding one hand stationary, he moves the other hand forward, or he may move both hands forward if desired. In either case, the forward movement of one or both hands will cause a rearward movement of the latch 15, which latch will pull back the stop 13 so that the switch arm 11 may be moved up to close the switch 10. At the same time, this rearward movement of the arm 15 will cause the switch 32 to open so that the circuit through the electro-magnet will again be open at this point. It will now be seen that the circuit cannot again be closed until both hands are moved rearwardly and out of the zone of danger. This is due to the fact that if one hand, say the left hand, is moved rearward while the right hand is maintained in a position of danger, the arm 16 will merely rock on its pivot and will not move the latch 15 sufficiently forward to close the switch 32. Likewise, if the right hand is moved rearward the arm 16 will merely rock on its pivot and will not sufficiently move the latch 15. Therefore, it will be seen that both arms must be moved rearward in order to close the switch 32.

Having thus described my invention, what

I claim as new and desire to secure by Letters Patent is—

1. In a device of the character described, the combination with a movable member for tripping the clutch of a press, of an electro-magnet for operating said movable member, a switch in the circuit of said electro-magnet opened by the operation of the electro-magnet, mechanical means for resetting said switch controlled by either of two members movable with the operator's hand, and a second switch in the electro-magnet circuit controlled by said members and arranged to be closed when both hands of the operator are out of the zone of danger. 80

2. In a device of the character described, the combination with a movable member for tripping the clutch of a press, of an electro-magnet for operating said movable member, a switch for controlling the circuit of said electro-magnet, mechanical means for closing said switch, hand-manipulated devices operating said means, said means being inoperative for closing the circuit of the electro-magnet when the hand-manipulated devices are individually operated, and operative for closing the circuit of the electro-magnet when the hand-manipulated devices are operated collectively and when both hands of the operator are out of the zone 95 of danger.

3. In a device of the character described, the combination with a movable member for controlling the clutch of a press, of an electro-magnet for operating said movable member, a switch opened by the movement of said electro-magnet, a movable member for causing said switch to be closed, a latch for operating the same, mechanism for operating the latch movable with the hands of the operator and operable for moving said movable member when either hand is moved toward the mechanism of the press, and a second switch closed by said mechanism, said mechanism being only operable to close 110 the switch when both hands of the operator are moved out of the zone of danger.

4. In a device of the character described, the combination with a movable member, of an electro-magnet for operating said movable member, a switch opened by the movement of said electro-magnet, a slid able stop for controlling the restoring of the switch, means for operating said stop to permit a restoring of the switch, a second switch 120 controlled by said means, a pair of movable members movable with the hands of the operator, and interdependent connections between the movable members and the slid able member for operating said slid able member to permit the restoration of the first switch upon the movement of either 125 of the pair of movable members when the hands are moved toward the press and for closing the second switch only when both 130

hands of the operator are moved out of the zone of danger.

5. In a device of the character described, the combination with a movable member for tripping the clutch of a press, of an electro-magnet for operating said movable member, a switch opened by said electro-magnet, an arm controlling the opening and closing of said switch, means tending to move said arm 10 to close the switch after it has been once opened, a stop moved into the path of the switch when the same is opened, means for moving the stop out of the path of the switch, a second switch, a rocker arm centrally pivoted on said means, a movable member moving with one hand of the operator connected to one end of said rocker arm, a movable member moving with the other hand of the operator connected to the 15 other end of said rocker arm, the connection being such that when one hand is moved toward the mechanism of the press the switch-controlling arm will restore the switch to closed position and when both 20 hands are moved out of the zone of danger the second switch will be closed to cause the operation of said electro-magnet.
6. In a device of the character described, a machine having a tool which moves in a 25 definite path, electromagnetic means for controlling the operation of said tool, and means for controlling the operation of said electromagnetic means, comprising a movable member, a rocker arm pivoted to said 30 member intermediate the ends of the arm, manually controlled means connected to one end of said rocker arm for actuating it, and manually controlled means movable independently of said first-named manually 35 controlled means connected to the other end of the rocker arm.

7. In a device of the character described, a machine having a tool movable in a definite path, electromagnetic means for controlling the operation of said tool, a switch 40 for controlling said electromagnetic means,

means for controlling said switch comprising a movable member, a rocker arm pivoted to said member, intermediate the ends of the arm, manually controlled means connected to one end of said rocker arm for actuating it, and manually controlled means movable independently of said first-named manually controlled means connected to the other end of the rocker arm. 50

8. In a device of the character described a machine having a part movable in a definite path, electromagnetic means for controlling the operation of said part, and means for controlling the operation of said 55 electromagnetic means comprising a movable member, two independently movable manually controlled means for acting on said member to move it, and means for so restricting the movement of said manually 60 controlled means that both must be operated to move said member sufficiently to cause the electromagnetic means to operate.

9. The combination with a hand feed machine having a part movable in a definite 65 path for operating on material, of means whereby the movement of either hand of the operator to a position adjacent the path of said part will prevent movement of said part, and whereby movement of both hands 70 of the operator to a position away from the path of said part will cause movement of said part, said means including a member constructed so that it is moved to one position when both hands of the operator 75 are adjacent said path, and so it is moved to another position when both hands of the operator are withdrawn, and so it is moved to an intermediate position when one hand only is withdrawn. 80

In witness whereof, I have hereunto subscribed my name in the presence of two witnesses.
